AERIAL FIRE EXTINGUISHER

Lawrence E. Carlson, Huntington, Ind., assignor
to Howard Stephen Carlson, West Branch,
Mich.

Application November 29, 1951, Serial No. 258,865

3 Claims. (Cl. 169—33)

1

This invention relates to a fire extinguisher bomb.

An object of this invention is to provide a fire extinguisher bomb which is adapted to be dropped from an airplane or other aircraft for putting out forest or other fires in relatively inaccessible places.

Another object of this invention is to provide a fire extinguisher bomb which is so constructed as to provide for a relatively wide broadcast 10 of the liquid when the bomb strikes the ground.

A further object of this invention is to provide an improved bomb which is formed of a frangible portion and a non-frangible portion so that a portion of the liquid will be dispersed 15 within the immediate area about the bomb, and the remaining liquid will be dispersed upward and beyond the immediate area around the bomb.

A further object of this invention is to provide an aerial bomb of this type with an improved means for filling the device with the fire extinguishing liquid.

A further object of this invention is to provide an improved aerial bomb which includes 25 means for maintaining the bomb vertical when the bomb is dropped, and for holding the same in a substantially upright position when the bomb strikes the ground.

A further object of the invention is to provide means whereby the course of the bomb in flight toward the target area may be observed for guidance and greater accuracy.

With the above and other objects in view, my invention consists in the arrangement, combination and details of construction disclosed in the drawing and specification, and then more particularly pointed out in the appended claims.

In the drawing:

Figure 1 is a detailed side elevation of an 40 aerial bomb fire extinguisher constructed according to an embodiment of this invention showing the bomb in operative or storing position.

Figure 2 is a vertical section taken substantially on the line 2—2 of Figure 1 showing the bomb in flight.

Figure 3 is a fragmentary sectional view taken on the line 3—3 of Figure 2.

Figure 4 is a fragmentary sectional view taken on the line 4—4 of Figure 2.

Referring to the drawing, the numeral 10 designates generally a cylindrical outer casing or shell which is formed at its lower end with a frusto-conical point 11. The casing 10 is formed of material which will readily shatter or break up when the device is dropped on the ground from a substantial height and may be formed out of either glass, brittle plastic or other suitable material. An inner cylindrical shell 12 is disposed within the outer shell 10 and is substantially shorter in length than the

2

outer shell. The inner shell 12 includes a bottom wall 13 which is formed with an offset opening 14 normally closed by means of a flap valve 15 which opens upwardly. The inner casing 12, including the bottom wall 13 and a top wall 16, is formed of relatively strong material, such as metal or the like, and is sufficiently strong so as to substantially retain its configuration after the bomb has contact with the ground. The lower end of the frusto-conical point 11 is normally closed by means of a disc-shaped plate 17, and a tubular member 18 is fixed relatively to the plate 17 and extends therebelow.

A conical cap 19 is threaded onto the tubular member 18 and engages partly about the plate or bottom wall 17. The wall 17 is formed with a threaded opening 20 within which a plug 21 is adapted to be disposed when the fire extinguishing liquid is contained within the bomb. The pipe 18 extends loosely through an opening 22 formed in the bottom wall 13, and pipe 18 has fixed thereto a plunger member 23 which is initially disposed in contact with the bottom wall 13. Plunger 23 is formed with an opening 24 adapted to register with the opening 14 and flap valve 15 is carried by the inner side of plunger 23. The top wall 16 is formed with a relatively large valve seat 25 and a conical member 26 is adapted to initially engage on the seat 25. The conical member 26 comprises a diffuser and is fixed to the upper end of tubular member 18. A guide 27 is disposed within the inner housing or shell 12 closely adjacent the upper end thereof for guiding the tubular member 18 as the inner shell 12 moves downwardly on the tubular member 18 after the bomb strikes the ground.

The tubular member 18 is formed with an opening 28 below the bottom wall 13 for communicating the interior thereof with the lower chamber 30 which is formed within the outer shell 10 below the bottom wall 13 of the inner shell 12. The tubular member 18 is also formed with a second opening 29 communicating the interior of tubular member 18 with the chamber 31 disposed within the inner shell 12. The openings 28 and 29 provide a means whereby the fire extinguishing liquid may be discharged into the chambers 30 and 31 by removing the conical cap 19 from the lower end of tubular member 18 and connecting the threaded lower end of tubular member 18 with a source of fire extinguishing liquid supply. When the chambers are being filled with the liquid, plug 21 is removed from the wall or plate 17 so that the chambers 30 and 31 may be exhausted as these chambers are being filled. The conical plug and diffuser 26 is sealed relatively to the upper end wall 16 and the seat 25 by means of thin frangible sheet 32 which is fixed to the upper wall 16. Cylindrical vane 33 is secured to a pair

of elongated bars 34 which are formed with elongated slots 35. The bars 34 overlap the outer shell or casing 10, and headed guide pins 36 extend through the slots 35 and provide for holding the guide vane 33 coaxial with the main body of the bomb.

A frangible screen 37 is fixed in the outer end of the vane 33 and includes a cylindrical side wall 37. A pair of flexible guiding tails 38 are fixed to the upper ends of the bars 34 by means of rings 39. The flexible tail members 38 are initially held within the cylindrical side wall 37 by means of an inverted U-shaped handle 40 which carries pins 41 removably engaging in openings 42 formed in the vane 33.

The handle 40 may be removed from the vane 33 by pressing the vane inwardly adjacent one of the pins 41 until the vane is distorted sufficiently to release the pin 41 from the opening 42. The handle 40 not only provides a means for holding the flexible tail members 38 in the outer end of the vane 33, but also provides a means whereby the vane 33 may be pulled outwardly to its extended guiding position, which is the position shown in Figure 2.

In the use of this extinguisher, the bombs may be stored in empty condition, and when the bombs are stored, the vane 33 will be disposed in inoperative position abutting against the upper end of the bomb body, as shown in Figure 1. When it is desired to fill the bomb, it is inverted, the cap 19 is removed from the plunger rod or tubular member 18, and a supply hose is connected with the threaded lower end of tubular member 18. As the liquid flows through the tube 18, and out of opening 29 into chamber 31, flap valve 24 drops open to permit the escape of air. When chamber 31 is filled with liquid, valve 24 closes, and the liquid then flows into chamber 30 through opening 28 in tube 18 until chamber 30 is filled, the air escaping through opening 20 in block plate 17. Screw plug 21 is then re-inserted in opening 20 and conical cap 19 replaced. When it is desired to drop the bomb, vane 33 is pulled outwardly to the position shown in Figure 2, and handle 40 is removed from vane 33. When the bomb is dropped from a substantial height, the air passing between the upper end of the bomb and the guiding vane 33 will tend to guide the bomb in a vertical drop and the air striking the wire screen will cause the flexible tails 38 to move upwardly to their operative position extending from the slide bars 34. As soon as the bomb strikes the ground or an object, the outer shell 10, which is highly frangible, will break thereby scattering the fire extinguishing liquid immediately within the area where the bomb fell. When the shell 10 below the inner shell 12 breaks, the lower end of plunger rod 18 will be forced into the ground to the depth permitted by the plate 17. The downward force of the falling of the bomb, including the striking of the ground, will cause inner shell 12 to move downwardly along the plunger rod 18, and at this time the thin sealing member 32 will be broken by the conical diffuser 26. As shell 12 moves downwardly, plunger rod 18 and conical diffuser 26 break through frangible screen 37, and simultaneously the liquid in chamber 31 will be forcibly discharged upwardly through opening 25 and at the same time this liquid will strike diffuser 26 so that the liquid will be dispersed or broadcast upwardly and outwardly within a relatively wide area.

I do not mean to confine myself to the exact 75

details of construction herein disclosed, but claim all variations falling within the purview of the appended claims.

What is claimed is:

1. An aerial fire extinguisher bomb comprising an outer cylindrical body formed of frangible material, a conical point at the lower end of said body, an inner non-frangible body in said outer body, said inner body dividing said outer body into an upper and a lower chamber, a tubular plunger rod disposed axially of said bodies, a plunger fixed to said rod and disposed in said upper chamber, said inner body including an upper end wall formed with a central opening, a conical diffuser fixed to the upper end of said rod and normally closing said opening, a frangible seal fixed to the outer side of said upper end and engaging over said diffuser, a cylindrical guide vane at the upper end of said outer body, a pair of slide bars fixed to said vane and extending over said outer body, said bars having elongated slots, guide pins carried by said outer body engaging through said slots, and a pair of flexible tail members secured to said vane.

2. An aerial fire extinguisher bomb comprising an outer cylindrical body formed of frangible material, a removable conical point at the lower end of said body, an inner non-frangible body in said outer body, said inner body dividing said outer body into an upper and a lower chamber, a tubular plunger rod disposed axially of said bodies, a plunger fixed to said rod and disposed in said upper chamber, said inner body including an upper end wall formed with a central opening, a conical diffuser fixed to the upper end of said rod and normally closing said opening, a frangible seal fixed to the outer side of said upper end and engaging over said diffuser, a cylindrical guide vane at the upper end of said outer body, a pair of slide bars fixed to said vane and extending over said outer body, said bars having elongated slots, guide pins carried by said outer body engaging through said slots, a U-shaped handle, and means detachably securing said handle to said vane.

3. An aerial fire extinguisher bomb and means for filling same comprising an outer cylindrical body formed of frangible material, a removable conical point at the lower end of said body, an inner non-frangible body in said outer body, said inner body dividing said outer body into an upper and a lower chamber, an end-threaded tubular plunger rod with openings disposed axially of said bodies, a block plate fixed to said rod and disposed near the lower extremity thereof, a plunger fixed to said rod and disposed in said upper chamber, said inner body including an upper end wall formed with a central opening, a conical diffuser fixed to the upper end of said rod and normally closing said opening, a frangible seal fixed to the outer side of said upper end and engaging over said diffuser, a cylindrical guide vane at the upper end of said outer body, a pair of slide bars fixed to said vane and extending over said outer body, said bars having elongated slots, guide pins carried by said outer body engaging through said slots, a cup-shaped frangible screen carried by said vane and forming a receptacle for said tails when the latter are inoperative, and a U-shaped handle removably secured to said vane and extending over said screen for retaining said tails therein.
